UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,374,937.

Specification of Letters Patent. Patented Apr. 19, 1921.

Application filed October 21, 1919. Serial No. 332,193.

To all whom it may concern:

Be it known that I, WILLIAM L. MCGRATH, a citizen of the United States, residing at Elmira, in the county of Chemung and State of New York, have invented certain new and useful Improvements in Engine-Starters, of which the following is a specification.

My invention relates to a starter for starting an engine such as an internal combustion engine, and the object thereof is to provide a simple, efficient and reliable drive or transmission therefor. My drive is of the well-known Eclipse-Bendix type characterized by 10 a rotatable member such as a screw shaft and a pinion automatically controlled in its movements by such shaft whereby when the prime mover such as the electric motor is operated the pinion is automatically meshed 15 with the engine member such as the fly wheel, and is automatically demeshed therefrom by reason of the greater speed of the engine. The various features of advantage 20 and utility in my new construction will be 25 apparent from the description hereinafter given.

In the drawings Figure 1 is an elevation partly in section illustrating the entire 30 starter system and a portion of the fly wheel of the engine; Fig. 2 an end elevation thereof; Fig. 3 a central longitudinal section of the drive or transmission showing parts of the lower portion in elevation; 35 Figs. 4 and 5 cross-sections on the lines 4-4 and 5-5 respectively of Fig. 3; and Fig. 6 a view similar to Fig. 3 but illustrating a modified form of construction.

Referring to the present embodiment of my invention as shown in the drawings 40 which embodiment may partake of different forms but which is here selected for the purposes of a clear description of my invention, the starter system comprises an electric motor 1 on whose armature shaft is secured 45 a driving pinion 2 which meshes with a gear 3. This gear is secured in a suitable manner as by means of a key 4 to one end of a casing or cylinder 5 which is here shown as of substantially two diameters. This gear 50 is mounted within an inclosing casing and bracket 6, being journaled therein by means of anti-friction bearings such as the ball bearings 7. The inner end of the casing 5, at the end opposite its attachment to the 55 gear 3, is supported by a collar revolving

around a stationary shaft 8 extending the full length of the casing 5, and also therebeyond at the right-hand end and supported in the bracket 9 which extends from the right-hand end plate 10 of the motor. This 60 shaft is screw-threaded at its extreme outer end and is held in position thereat by means of the nut 11.

The drive proper which is contained within the casing 5 is substantially an Eclipse-Bendix drive with certain modifications to adapt it for this particular construction. As shown a driving head comprising a flange 12 and an annular hub 13 is mounted loosely upon the shaft 8 and such flange is interlocked at its edge to the right-hand end of the cylinder 5, such parts being held in place by means of the ring 14 screwing upon such cylinder.

The driving head is operatively connected 75 by means of a yielding driving connection such as the coiled spring 15 with the driven head 16 of the rotatable member such as the hollow screw shaft 17, which is mounted loosely upon the shaft 8. The drive spring 80 is anchored as usual to the driving and driven heads by the studs 18 and 19 respectively. The screw shaft is provided at its outer end with the usual stop nut 20.

The driving member which is adapted to 85 engage a part of the engine to be started, such as the fly wheel 21, comprises a pinion 22 which is mounted loosely upon the extreme outer end of the stationary shaft 8, and a cylindrical extension or shell 23 projecting inwardly and over the screw-threaded 90 portion of the shaft 17. This shell is internally screw-threaded so as to coöperate with the screw threads of the shaft 17. In the present instance the screw threads of the 95 shell are formed separately, the same being formed in the inner bore of a sleeve 24 which is provided at its outer end with an annular flange 25 interlocked with the inner or right-hand end of the shell 23. These 100 parts are held together by means of the ring 26 screwing onto the shell.

Describing a cycle of operation, when the motor is started the gear 3 will be rotated. As a result the entire cylinder 5 and the 105 driving heads and screw shaft therewithin will be rotated around the stationary shaft 8 as an axis and as a support. The pinion 22 will thereupon be advanced longitudinally of the screw shaft and into mesh with 110

the fly wheel gear. The screw threads of the shaft 17 and sleeve 24 are loosely fitted and the pinion 22 is likewise loosely fitted upon the extreme reduced diameter end of the shaft 8 so that the weight of the pinion and its shell bears upon the upper surface of the stationary shaft sufficiently to cause friction to retard or prevent any tendency of the pinion to rotate at this time, which in 10 addition to its inertia insures the desired longitudinal movement thereof. The pinion continues to advance longitudinally until the screw sleeve 24 comes into contact with the stop nut 20, whereupon such pinion will 15 partake of the rotary movement of the screw shaft and will thereby rotate the fly wheel. When the engine starts on its own power the pinion will be automatically demeshed and returned to normal position in the well-known manner.

In Fig. 6 I have shown a modified form of construction which differs from that described, more particularly in the stop means for the advancing longitudinal movement 25 of the pinion. In this modification the corresponding parts are similarly indicated. The stop nut 20 is here dispensed with and stop means provided which co-operates with the exterior of the pinion shell. As shown 30 the screw shaft is provided intermediate its length and at the rear of its screw-threaded portion with a circumferential flange 27 which is interlocked with a forwardly extending cylinder 28, such parts being held 35 together where interlocked by the ring 29 screwing upon such cylinder. This cylinder fits within the outer end or bore of the main cylinder 5 and is provided at its outer end with an inwardly directed flange 30 forming on its inner side a stop shoulder 31. The pinion shell 23 is provided with a circumferential flange 32 thereby providing a forward shoulder 33 adapted to abut the shoulder 31 when the pinion is at its limit of out- 40 ward longitudinal position, at which time the pinion and its shell together with the cylinder 28 partake of the rotary movement of the screw shaft. In other respects the construction and mode of operation are the 45 same as that above described.

The loose fit between the screw threads and between the pinion and its supporting shaft assure the longitudinal advancement of the pinion due to the resulting friction, 55 but it will be understood that when the pinion is rotating it necessarily becomes centered, besides which provision is made for such centering in the bearing provided at the outer bore of the cylinder 5 which then 60 co-operates with the flange 34, in the form shown in Fig. 3, or at the outer bore of the shell 30 which then co-operates with the flange 35, in the form shown in Fig. 6.

I claim:

65 1. An engine starter drive comprising a

central support, a sleeve mounted thereon, a concentric cylinder operatively connected with the sleeve, means for rotating the cylinder, and a driving member operatively connected with the sleeve for longitudinal 70 movement thereof and rotary movement therewith.

2. An engine starter drive comprising a central support, a sleeve mounted thereon, a concentric cylinder, a yielding driving connection between the cylinder and sleeve, means for rotating the cylinder, and a driving member operatively connected with the sleeve for longitudinal movement thereof and rotary movement therewith. 75

3. An engine starter drive comprising a central support, a sleeve mounted thereon, a concentric cylinder, a yielding driving connection between the cylinder and sleeve, consisting of a drive spring, means for rotating the cylinder, and a driving member operatively connected with the sleeve for longitudinal movement thereof and rotary movement therewith. 80

4. An engine starter drive comprising a central support, a sleeve mounted thereon, a concentric cylinder, means for rotating the cylinder, a driving head loosely mounted on the support and connected with the cylinder, an operating connection between the head 90 and sleeve, and a driving member operatively connected with the sleeve for longitudinal movement thereof and rotary movement therewith. 95

5. An engine starter drive comprising a central support, a sleeve mounted thereon, a concentric cylinder, means for rotating the cylinder, a driving head loosely mounted on the support and connected with the cylinder, a drive spring anchored to the head and 100 sleeve respectively, and a driving member operatively connected with the sleeve for longitudinal movement thereof and rotary movement therewith. 105

6. An engine starter drive comprising a central support, a rotatable sleeve mounted thereon, means for rotating such sleeve, and a driving member operatively connected with the sleeve for longitudinal movement thereof and rotary movement therewith, 110 said member being mounted to slide on said support. 115

7. An engine starter drive comprising a central support, a rotatable sleeve mounted thereon, means for rotating such sleeve, and a driving member operatively connected with the sleeve for longitudinal movement thereof and rotary movement therewith, said member being arranged axially of said sleeve and support and mounted to slide on such 120 support. 125

8. An engine starter drive comprising a central support, a rotatable sleeve mounted thereon, means for rotating such sleeve, and a driving member operatively connected 130

with the sleeve for longitudinal movement thereof and rotary movement therewith, said member being mounted to slide upon one end of such support and in front of the sleeve.

9. An engine starter drive comprising a central support, a rotatable sleeve mounted thereon, means for rotating such sleeve, and a driving member operatively connected with the sleeve for longitudinal movement thereof and rotary movement therewith, said member being mounted to slide on the support and such member and sleeve having co-operating stop means for limiting the outward longitudinal movement of the member.
- 10
- 11
- 12
- 13
- 14
- 15

10. An engine starter drive comprising a central support, a rotatable sleeve mounted thereon, means for rotating such sleeve, and a driving member operatively connected 20 with the sleeve for longitudinal movement thereof and rotary movement therewith, said member having a body portion mounted to slide on the support and a shell portion having said operative connection with the sleeve.

25 11. An engine starter drive comprising a central support, a rotatable sleeve mounted thereon, means for rotating such sleeve, and a driving member operatively connected with the sleeve for longitudinal movement
30 thereof and rotary movement therewith, said sleeve having external screw threads, and said member having a body portion mounted to slide on the support and a shell portion having internal screw threads co-operating
35 with the screw threads of the sleeve.

12. An engine starter drive comprising a central support, a rotatable sleeve mounted thereon, means for rotating such sleeve, and a driving member operatively connected
40 with the sleeve for longitudinal movement thereof and rotary movement therewith, said sleeve having external screw threads, and said member comprising a pinion mounted to slide on the support and a shell
45 portion having internal screw threads co-operating with the screw threads of the sleeve.

13. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support.

14. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads

and said member comprising a pinion having a shell extension and a sleeve nut screw-threaded onto its sleeve, said pinion being mounted to slide upon the support, and said nut being rigid with such extension.

15. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, and means for limiting the longitudinal movement of the pinion. 75 80

16. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, and means located within such extension for limiting the longitudinal movement of the pinion. 85 90 95

17. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, and a stop nut arranged at the outer end of the threads of the sleeve and adapted to be contacted by the sleeve nut to limit the longitudinal movement of the pinion. 100 105 110

18. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, said pinion having a loose sliding fit upon said support so as to have frictional contact therewith except when rotated. 115 120 125

19. An engine starter drive comprising a central support, a rotatable sleeve mounted thereon, means for rotating such sleeve, and a driving member operatively connected 130

with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, said cooperating screw threads being loosely fitted and said pinion having a loose sliding fit upon said support so as to have frictional contact therewith on its top surface except when rotated.

20. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion having a shell extension and a sleeve nut screw-threaded onto its sleeve, said pinion being mounted to slide upon the support, and said sleeve nut being interlocked with the extension.

25. An engine starter drive comprising a central support, a rotatable sleeve mounted thereon, means for rotating such sleeve, and a driving member operatively connected with the sleeve for longitudinal movement thereof and rotary movement therewith, said sleeve having external screw threads and said member comprising a pinion hav-

ing a shell extension and a sleeve nut screw-threaded onto its sleeve, said pinion being mounted to slide upon the support, and said sleeve nut consisting of a sleeve portion and a flange portion interlocked with the extension.

22. An engine starter drive comprising a central support, a sleeve mounted thereon, a concentric cylinder, means for rotating the cylinder, a driving head loosely mounted on the support and connected with the cylinder, such head consisting of a collar portion surrounding the support and a flange portion connected with the cylinder, an operating connection between the head and sleeve, and a driving member operatively connected with the sleeve for longitudinal movement thereof and rotary movement therewith.

23. An engine starter drive comprising a central support, a sleeve mounted thereon, a concentric cylinder, means for rotating the cylinder, a driving head loosely mounted on the support and connected with the cylinder, such head consisting of a collar portion surrounding the support and a flange portion interlocked at its edge with one end of the cylinder, an operating connection between the head and sleeve, and a driving member operatively connected with the sleeve for longitudinal movement thereof and rotary movement therewith.

WILLIAM L. McGRATH.
